US0D1053843S

(12) **United States Design Patent** (10) **Patent No.:** **US D1,053,843 S**
(45) **Date of Patent:** ** *Dec. 10, 2024

(54) **HEADPHONES**

(71) Applicant: **Focusrite Audio Engineering Limited**,
High Wycombe (GB)

(72) Inventors: **Orla Haigh**, Cheltenham (GB); **Ryan Gray**, Hazlemere (GB); **Joshua Wilkinson**, Aylesbury (GB)

(73) Assignee: **Focusrite Audio Engineering Limited**,
High Wycombe (GB)

(*) Notice: This patent is subject to a terminal disclaimer.

(**) Term: **15 Years**

(21) Appl. No.: **29/865,922**

(22) Filed: **Aug. 20, 2022**

(30) **Foreign Application Priority Data**

May 27, 2022 (GB) 6211054

(57) **CLAIM**

The ornamental design for a headphones as shown and described.

DESCRIPTION

FIG. 1 is a front perspective view of the headphones;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings forming the words “vocaster studio”, “vocaster”, and “HP60V” depict portions of the headphones that form no part of the claimed design.

1 Claim, 7 Drawing Sheets
